ELECTRIC SWITCH

William Correll Edwards, Anderson, Ind., assignor to General Motors Corporation, Detroit, Mich., a corporation of Delaware

Application February 23, 1935, Serial No. 7,915

12 Claims. (Cl. 201—48)

This invention relates to electric switches for automotive vehicles and more particularly to switches for controlling translation devices, such as lamps, and for concurrently controlling a resistance unit associated with an instrument, such as a generator.

Herein is disclosed in the present invention a plurality of switches that are used for the purpose of controlling the various lamp circuits of an automotive vehicle in conjunction with an auxiliary switch for controlling the output of a generator. The auxiliary switch is operable upon actuation of one of the switches for the lamps, or other heavy loads to short circuit a resistance unit connected in the generator field circuit. In the normal position of the auxiliary switch the resistance unit is included in the field circuit so as to reduce the output of the generator when it might be otherwise entirely too high for charging a normal size storage battery continuously. When the auxiliary switch is operated to include lamps or other heavy current devices the resistance unit is short circuited to allow the increased load to take care of the increased output of the generator.

Among the objects of the present invention is to provide a simple and economical switch construction whereby a single control member will coincidentally operate the means for controlling the current flow to the translation devices and the means for controlling the resistance unit to control another instrument. This is accomplished by providing a switch construction which includes a movable member of insulating material carrying a bridging member adapted to connect the translation devices in a circuit and also having a plate movable with the insulating member, the plate having provisions whereby the resistance unit is insulated from the switch case in a certain position of the switch, while in another position of the switch the resistance unit is mechanically connected with the plate to ground the resistance unit through the switch case.

Further objects and advantages of the present invention will be apparent from the following description, reference being had to the accompanying drawings wherein a preferred embodiment of the present invention is clearly shown.

In the drawings:

Fig. 1 is a plan view, partly in section, of the switch structure embodying the present invention.

Fig. 2 is a sectional view taken on the line 2—2 of Fig. 1.

Fig. 3 is a sectional view taken on the line 3—3 of Fig. 2.

Fig. 4 is a rear view of the structure substantially as indicated by the arrow 4 of Fig. 2.

Fig. 5 is a sectional view taken on the line 5—5 of Fig. 2.

Fig. 6 is a sectional view taken substantially on the line 6—6 of Fig. 1.

Figs. 7, 8 and 9 are circuit diagrams showing the different position of the switch parts and the various circuits which are closed by the operation of the switch.

Referring to Figs. 1 to 6 inclusive of the drawings, a supporting bracket or mounting plate 20 of sheet metal is provided with legs 21 and 22. The leg 21 is suitably apertured to receive bolt and nut devices, not shown, for attaching the bracket to a suitable support or to an instrument panel 23 of an automotive vehicle. A cup-shaped housing 24 is provided with a flat wall 25 and is secured to the leg 22 of the bracket in any preferred manner, such as spot welding or the like.

The flat wall 25 of the cup-shaped housing 24 and the leg 22 of the bracket are provided with aligned apertures 26, 27, and elongated or guide openings 28. Adjacent the flat wall 25 there is placed a flat ground plate or disc 29. This disc 29 has an opening 30 substantially the diameter of the opening 26. The portion margining the opening 30 is inwardly extended to provide a tongue or projection 31. The plate 29 is also provided with a radial slot 32 and an arcuate opening 33. The slot 32 has communication with the elongated openings 28 while the arcuate slot has communication with the apertures 27.

The openings 26 in the flat wall 25 and the leg 22 provide a journal bearing for a hub 34 of a non-conducting drive member 35. This member is provided on one side with a radial slot 36 so as to communicate with the radial slots 32 of the disc 29 and the elongated openings 28. Thus, when the member 35 is placed in position, the hub 34 is journaled in the openings 26 and the tongue 31 of the plate 29 will fit into the slot 36 so that the plate 29 will be driven by the member 35.

The drive member 35, carries a movable contact plate or circuit completing member 40 of disc formation. This plate has contact bosses 41, 42 and 43 arranged in triangular formation. At points intermediate the contact bosses 41, 42 and 43 the plate is provided with tongues or projections 44 punched therefrom. These tongues or projections are adapted to extend into suitable notches provided by the drive member 35. The arrangement and dimensions of the tongues 44 relative to their respective notches are so proportioned and arranged that the member 40 will

have a relatively loose driving engagement with drive member 35 and capable of axial movement along the axis thereof.

A coiled spring 50 is interposed between the 5 contact plate 40 and the member 35. One end of the spring rests against the plate 40 while the other end rests on the bottom of an annular recess 51, as shown in Fig. 2. The bottom of the recess 51 is provided with a radial depression or recess 52, said channel having an opening which communicates with the radial slot 36. The channel 52 forms an anchoring means for one end of a leaf spring 53 located in the radial slot. The radial slot 36 of the drive member 35 is gauged as at 54 to receive the free end of the spring.

A switch back or closure 59 of insulating material supports a battery connection 60 and a plurality of contact terminals 61, 62, 63, 64, 65 20 and 66 arranged in a circular row. The contact terminals are provided with contact surfaces within the housing. The contact terminals 61 and 64 are connected together by a plate 67. Both the battery connection 60 and the plate 25 67 are provided with fuse brackets for the retention of a fuse 68. The back 59 operates to close the open end of the cup-shaped housing 24 and is secured to the housing by bending over tangs 69 formed integral with the housing. The securing of the back to the housing will cause the spring 50 to be compressed between the contact plate 40 and the driving member 35. The spring, while under compression, urges the plate axially so that the contact bosses 41, 42 and 30 43 bear against the back and at the same time causes the member 35 to urge the ground plate 29 against the flat wall 25 of the housing and also keeps the boss 34 within the openings 26.

The actuating means for the switch comprises 40 a push-pull rod 70 having an end 71, bent at substantially right angles to the main portion of the rod. The end 71 extends through the elongated opening 28, the radial slot 32 of the ground plate 29 and into the radial slot of the member 35 to bear against the free end of the spring 53, located in the gauged portion of the slot 36. The spring 53 is put under tension by the end 71 and the spring operates to prevent rattles or noises between the rod and other switch parts. 45 The other end of the rod 70 is slidably supported in a bushing or sleeve 72. This bushing extends through suitable openings provided by leg 21 and the support 23. The bushing is provided with a shoulder 73 that bears against the support 23 so that when a nut 74 is screw-threaded upon the threaded portion of the sleeve and drawn tightly against the leg 21, the main portion of the rod will move in a plane substantially 50 parallel to the leg 22 and maintain the end 71 in the radial slot 36. The rod 70 is provided with a knob 75 which facilitates the movement of the same to rotate or oscillate the drive member 35 which in turn rotates the circuit completing means and the ground plate. The rod is limited in its movement by the end edges of the 55 elongated openings 28.

Associated with the switch is a resistance unit assembly 80. This assembly is insulatingly supported upon the leg 22 as clearly shown in Fig. 70 6. The assembly includes a resistance coil 81 and a plate 82 carrying a contact 83. The contact 83 extends through the apertures 27 of the leg 22 and flat wall 25 and normally extends through the arcuate slot 33 of the ground plate 29 to engage the non-conducting drive member 35, as

shown in Figs. 5 and 6, so as to include the resistance coil 81 in a circuit.

The use of the switch construction shown in Figs. 1 to 6 inclusive is preferably embodied in a system of electrical distribution as disclosed in Figs. 7, 8 and 9. In these figures 100 designates a generator which is driven at variable speed by an internal combustion engine. The generator includes main brushes 101 and 102 10 the former being grounded and the latter being connected to a lead 103 which is connected to one side of a cut-out relay 104. The other side of the relay is connected to a battery 105. The cut-out relay automatically connects the generator with the battery when the generator voltage exceeds a certain value and disconnects the battery from the generator where the voltage of the generator falls below a certain value. A third brush 106 is connected with the shunt field 107 which is connected by a lead 108 with the plate 82 which is electrically connected to one 15 end of the resistance coil 81. The other end of the coil is connected to ground.

The different positions of the switch to close various circuits will be obvious from Figs. 7, 8 and 9. It will be seen that a horn 110 is connected to the connector 67 fixed to the switch back through the lead 111 so that the horn will be included in a circuit in either position of the 20 switch in case the operator closes a switch 112, 30 the horn will be operated.

The different lamp circuits are connected through the switch by the various terminal connectors on the back of the switch closure 59. Head lamps 115 are connected to the terminals 63 by a lead 116. Parking lamps 117 are connected to the terminal 62 by a lead 118 and the tail light 119 is connected to the terminal 65 by a lead 120.

The novel feature of the invention resides in 40 the use, in connection with the electrical system described and illustrated, of the resistance coil which is supported and controlled by the switch structure and which is connected directly to the generator field circuit. When the switch 45 is in its "off" or "park" positions and the battery is fully charged it is necessary to have some means to cut down the out-put of the generator so as not to cause serious damage to the electrical system. This is accomplished by the resistance coil 81. The resistance coil 81 functions when the use of lamps is not necessary or when lamps having a light load are used to stabilize the load. When the switch is in the "on" position, or in other words when the head lamps 55 are burning, the resistance coil is shorted out and the field circuit is connected directly to ground so as to insure full output of the generator.

Thus, when the switch mechanism is in the 60 position shown in Fig. 7, the resistance coil 81 is connected in the field circuit, as the contact 83 extends through the arcuate slot 33 of the ground plate 29, as clearly shown in Fig. 5; and bears against the non-conducting drive plate 35. 65

When the switch is actuated from the position shown in Fig. 7 to that shown in Fig. 8 the contact 83 still extends through the arcuate slot 33 and bears against the non-conducting plate 35, and the following circuits are completed to the tail lamp 119 and the side lamps 117 with the resistance 81 connected in the field circuit 108 in the following manner: from the battery 105, lead 99, terminal 60, fuse 68, connector 61, contact 64, contact plate 40, and then 75

the current is divided, a portion of the current flowing from the plate 40 through terminal 62, lead 118, lamps 117 then back to the battery through ground, while another portion of the current will be directed from the plate 40 to the terminal 66, connection 121, terminal 65, lead 120, tail lamp 119 and back to the battery through a ground connection.

When the switch is moved to the position shown in Fig. 9 to connect the head lamps 115 in a circuit together with the tail lamp circuit, the following circuits are completed: from the battery 105, lead 99, terminal 60, fuse 68, terminal connection 67, terminal 61, plate 40, and then the current is divided, a portion of the current will be directed from the plate 40 through terminal 63, lead 116, head lamps 115 then back to the battery through a ground connection, while another portion of the current will be directed from the plate 40, terminal 65, lead 120, tail lamp 119, then back to the battery through the ground connection. While the switch is in the position shown in Fig. 9, the resistance coil 81 is short circuited as the field circuit 107 of the generator 100 is connected directly to ground through lead 108, plate 82, contact 83, plate 29 to ground.

While the embodiment of the present invention as herein disclosed, constitutes a preferred form, it is to be understood that other forms might be adopted, all coming within the scope of the claims which follow.

What is claimed is as follows:

1. An electric switch comprising, in combination; a bracket; a housing secured to the bracket; a closure member secured to the housing and providing a plurality of contact terminals; a circuit closing means rotatably supported within the housing for cooperation with the terminals 40 to close a plurality of circuits; a ground plate rotatable with the circuit closing means; a resistance unit insulatingly supported on the bracket, said unit having a contact normally disengaging the ground plate to maintain the resistance in a circuit; and a controller operable upon the circuit closing means to move the ground plate in engagement with the contact to short circuit the resistance unit.

2. An electric switch comprising, in combination; a mounting plate; a cup-shaped housing secured to the plate; a closure member secured to the housing and providing a plurality of contact terminals; a circuit closing mechanism rotatably supported within the housing; a short-circuiting plate located adjacent the flat wall of the housing and rotated with the circuit-closing mechanism; a resistance unit assembly insulatingly supported on the mounting plate, said assembly comprising a resistance coil and a plate carrying a contact, said contact extending through aligned openings in the mounting plate and the flat wall of the housing to make engagement with a non-conducting part of the circuit closing means so as to connect the coil in certain circuit closing positions of the switch; and a controller operable on the circuit-closing mechanism to move same in a certain circuit closed position and connect the short circuiting plate with the contact so as to short circuit the resistance coil.

3. An electric switch comprising, in combination; a mounting plate; a housing secured to the plate; a closure member secured to the housing and providing a plurality of contact terminals; a circuit closing means rotatably sup-

ported within the housing for cooperation with the terminals to complete a plurality of circuits; a short circuit member carried by the circuit closing means and having engagement with the housing; a resistance unit assembly comprising a resistance coil and a plate carrying a contact, said contact having engagement with a non-conducting part to maintain the resistance coil in a circuit; and a controller operable with the circuit closing means to close a certain circuit and move the short circuit member into engagement with the contact so as to short circuit the resistance coil.

4. A switch for controlling the field circuit of a generator comprising, in combination; a mounting plate; a cup-shaped housing secured to the plate; a closure member secured to the housing and providing a plurality of contact terminals; a circuit closing means rotatably supported within the housing for cooperation with the terminals to close a plurality of lamp circuits; a ground plate located within the housing and rotatable with the circuit-closing means; a resistance unit assembly insulatingly supported on the mounting plate and connected with the field circuit of the generator, said assembly comprising a resistance coil and a plate carrying a contact extending into the housing and normally held out of engagement with the ground plate so as to include the resistance coil in the field circuit; and manually operable means for moving the circuit closing means to close a lamp circuit and connect the ground plate with the contact to short-circuit the resistance coil.

5. An electric switch comprising, in combination; a bracket having an aperture and an elongated opening; a cup-shaped housing supported by the bracket and having an aperture and an elongated opening in alignment with the aperture and the opening of the bracket; a non-conducting drive plate having a hub portion journaled in the housing and the bracket and having a radial slot in communication with the elongated openings; a ground plate drivingly connected with the non-conducting plate and having an arcuate slot and a radial opening in communication with the elongated openings; a contact member provided with extensions loosely received by notches of the drive plate; a terminal plate closing the back of the housing and providing a plurality of contacts in cooperative relation with the contact member; means disposed between the drive plate and contact plate maintaining engagement of the contact plate with the terminal plate; an operating rod slidably supported on the bracket and having a transverse portion extending through the elongated openings and the radial opening of the ground plate and into the radial slot of the drive plate whereby the drive plate and the ground plate may be oscillated upon actuation of the rod; and a resistance unit assembly insulatingly supported on the bracket, said assembly comprising a resistance coil and a plate carrying a contact extending through the aligned apertures of the bracket and housing and the arcuate slot of the ground plate to normally engage the non-conducting drive plate to maintain the resistance coil in a circuit in certain positions of the switch, and said contact engaging the ground plate in another position of the switch to short circuit the resistance coil.

6. A switch for controlling the field circuit of a generator comprising in combination; a housing; contact terminals insulatingly supported by the housing; a circuit closing means rotatably sup-

- supported within the housing for cooperation with the terminals to close a plurality of circuits; a ground plate located within the housing and rotatable with the circuit closing means; a resistance unit assembly insulatingly supported with respect to the housing and connected with the field circuit of the generator, said assembly including a contact extending into the housing and normally held out of engagement with the ground plate so as to include the resistance coil in the field circuit; and manually operable means for rotating the circuit closing means and the ground plate a certain distance toward a circuit closing position to connect the ground plate with the contact to short circuit the resistance coil.
7. A switch for controlling the field circuit of a generator comprising in combination; a housing; contact terminals insulatingly supported by the housing; a circuit closing means rotatably supported within the housing for cooperation with the terminals to close a plurality of circuits; a ground plate located within the housing and rotatable with the circuit closing means; a resistance unit assembly insulatingly supported with respect to the housing and connected with the field circuit of the generator; and means to short circuit the resistance through the ground plate in one of the circuit closing positions of the switch.
- 30 8. A switch for controlling the field circuit of a generator comprising in combination; a housing; contact terminals insulatingly supported by the housing; a circuit closing means rotatably supported within the housing for cooperation with the terminals to close a plurality of circuits; a ground plate located within the housing and rotatable with the circuit closing means; a resistance unit assembly insulatingly supported with respect to the housing and connected with the field circuit of the generator, and means to short circuit the resistance, said means including a contact adapted to engage the ground plate and operable to short circuit the resistance intermediate circuit closed positions of the switch.
- 45 9. A switch having "off" and "on" positions comprising, in combination; a housing; a closure member secured to the housing and providing a plurality of contact terminals; a circuit closing means rotatable within the housing cooperating with the terminals to close a plurality of circuits; a ground plate rotatable with the circuit closing means; a resistance unit insulatingly supported with respect to the housing to control a circuit for an instrument, said unit having a movable contact associated therewith and normally out of engagement with the ground plate whereby the resistance will be included in the instrument circuit in the "off" position of the switch; and means operable with the circuit closing means to rotate the same in an "on" position of the switch to include the resistance unit in the instrument circuit and to short circuit the resistance through the ground plate and the housing when the circuit closing means is rotated to another "on" position.
- 50 10. A switch comprising in combination; a mounting member; a housing secured to the mounting member; an insulating block secured to the housing and providing a plurality of contact terminals; a circuit closing means rotatably supported within the housing for cooperation with the terminals to close a plurality of circuits; a plate carried by the circuit closing means and cooperating with the housing to provide a ground connection; a resistance unit insulatingly supported on the mounting member, said unit having means extending into the housing and normally out of engagement with the plate; and means for transmitting movement to the plate and the circuit closing means simultaneously to close circuits of different loads, the extending means being arranged relative to the plate so that the resistance unit will be in a circuit of light loads and short circuited through the ground connection by the extending means through the plate when circuits of heavy load are closed.
- 55 11. A switch for controlling the flow of current to translating devices having an "off" position and several "on" positions comprising in combination; a housing; a closure for the housing and providing a plurality of contact terminals; a floating contact member supported for rotatable engagement with the terminals; a resistance unit insulatingly supported with respect to the housing for controlling another instrument; and grounding means for the resistance unit, said means rotatable with the floating contact member but insulated therefrom and arranged therewith so that the resistance unit will be included in the circuit to the instrument in the "off" and the first "on" position of the switch and short circuited when the switch is moved to a second "on" position.
- 60 12. A switch for controlling a plurality of lamp circuits and the field circuit of a generator comprising, in combination; a housing; contact terminals insulatingly supported by the housing; a circuit closing means rotatably supported within the housing for cooperation with the terminals to close a plurality of lamp circuits having different loads; a ground plate rotatable with the circuit closing means; a resistance unit insulatingly supported with respect to the housing and connected with the field circuit of the generator; said unit including a contact normally held out of engagement with the ground plate so as to include the resistance in the field circuit in the "off" position of the switch; and manually operable means for rotating the circuit closing means and the ground plate simultaneously in an "on" position of the switch to close a circuit to a set of lamps of a certain load and include the resistance in the field circuit and to short circuit the resistance through the ground plate when the circuit closing means is rotated to another "on" position to close a circuit to a set of lamps of a greater load.
